UNITED STATES PATENT OFFICE.

EDWARD S. MCKINLAY, OF DENVER, COLORADO.

MINING-MACHINE.

SPECIFICATION forming part of Letters Patent No. 550,895, dated December 3, 1895.

Application filed February 11, 1889. Serial No. 299,548. (No model.)

To all whom it may concern:

Be it known that I, EDWARD S. MCKINLAY, a citizen of the United States, residing at Denver, in the county of Arapahoe and State of Colorado, have invented certain new and useful Improvements in Mining-Machines, of which the following is a specification, reference being had therein to the accompanying drawings.

10 Figure 1 is a plan view of my machine, showing the manner of attacking the coal. Fig. 2 is a section on line $x'x$, Fig. 1. Fig. 3 is a section on line $y'y$, Fig. 1. Fig. 4 is a section on line $x'x'$, Fig. 8. Fig. 5 is a longitudinal section of one of the drill-cylinders, enlarged. Fig. 6 is a plan view of part of the cutter-carrier. Fig. 7 is a cross-section through the cutter-carrier. Fig. 8 is an enlarged view of the carrier-feeding cylinder with its adjacent parts. Fig. 9 is a view looking in the direction of the arrow in Fig. 8. Fig. 10 is a section on line x^2x^2 , Fig. 8. Fig. 11 shows part of the carriage-feeding mechanism. Figs. 12, 13, 14, 15, 16, and 17 show details of the same. 25 Figs. 18, 19, and 20 show a modified form of the chain-driving devices.

20 A represent the side parts of a frame adapted to be made stationary temporarily and to support the movable and operative parts of the apparatus. As shown, these tubes and the framework of which they constitute a part can be extended from time to time by connecting sections endwise one after the other, in the manner described and shown 35 in an earlier application, Serial No. 279,696, filed by me July 11, 1888.

30 B² are cross-bars having eyes or short sleeves B' B', adapted to fit the tubes A and to be secured thereto by set-screws b.

40 B³ B³ are standards for supporting the frame, they resting on pedestals b' and being threaded and provided with cranks or handles at b² for rotating them in the threaded ears B⁴ on the eyes or sleeve B'. On the frame 45 so provided a movable carriage is mounted, having a plate C, with eyes or supporting-sleeve C' surrounding side parts A A.

50 c c are antifriction-rollers in chambers formed in the sleeve or eyepieces C' and resting on side parts A A.

From carriage C is supported the revolving table or wheel D, supported on a pivot D'. It has peripheral worm-teeth engaging with

worm D⁵, rotated by bevel-gear D³ and hand-wheel D⁴.

55 From table or wheel D is supported the driving-cylinder E, which pushes the cutters inward and draws them out. The piston E' projects toward the material to be cut. On it is supported a frame or cutter-carrier G, to which the drills or several cutting mechanisms H H are secured. These drills are of a class now well known, the cutting action of each being effected by exceedingly-rapid reciprocation of a hammer H', driven by air-pressure against a drill-holder H², the cutter being shown at h. Air is fed to and exhausted from the ends of the cylinder alternately.

60 The frame or carrier G is shown as made of two plates g g', bolted together and provided with air-ducts g² g³. The duct g² is connected to the feed sides of the pistons through ports, as at g⁵, and the exhaust-ports are turned toward the cutters, so as to assist in throwing 65 out the cuttings. The carrier-plates g g' may be cast with longitudinal grooves in their inner faces to form the air-ducts g² g³, and the lateral ducts at g⁵ g⁶ may be formed by drilling. The air passes to the duct g² through 70 a pipe I, here intended to be a flexible hose, there being a valve at I' to regulate the admission of the air at the end i of duct g². The duct g³ receives air from pipe J through 75 valve J'. The air so admitted can be used to assist in cleaning the cuttings when such cleaning is necessary, and at other times this duct can be closed by the valve J'. The valves I' and J I may be dispensed with, and the valve at j' j² used instead thereof.

80 K is a reservoir or pipe connected by a hose K' with a stationary feed-pipe arranged at some suitable place near where the cutting is to be performed. The reservoir or pipe K and coupling for the connection of the various 85 valves and pipes or hose which are to carry the air in the several directions are provided with valves, (shown at j j' j² j³), together with the aforesaid pipes I J L L'. Through pipe L passes the air to cylinder E, there being a 90 pipe at M, extending to the ports m m' and communicating with the pipe L through a valve L². Valve L² has a handle m², which is adapted to be thrown alternately in opposite directions by parts carried by the piston E'. 95 E² is a cross-head on piston-rod E'.

N is an arm pivoted at n to the cross-head. n' is a guide on arm N, it being fitted to a guide-plate O, having a way with the parts o' and rib o² between. When bar N moves backward, guide n' travels in the part o', and when advancing it moves in the part o. There is a cam-latch at o³, which lifts it from part o to part o' of the way. Bar N has projections n² n³ in the path of handle m² of valve L², and said projections alternately admit the air through the opposite ends of the cylinder E. In this way the parts carried by the piston can be caused to automatically effect the advancing and receding thereof. Of course other devices of any suitable construction can be substituted for those shown.

N' is a cam on bar N, which it is desired to alternately elevate and depress and for which purpose use is made of the two-part guide-way above described.

Air-pressure is used to also give to the carriage C and the parts supported thereon a step-by-step movement forward.

25 S is a cylinder, the piston-rod S' of which is pivoted at s to carriage-plate C. The air passes from pipe K through hose L, valve t, and pipe T to cylinder S. The piston is prevented from moving until the cutters are drawn back by piston E'. Just as they reach the outermost point in their travel the aforesaid cam N' pushes up on rod P. This elevates the segment-piece P' on table or wheel D, which in turn throws up the end of lever Q. This lever is pivoted to the under side of carriage-plate C at q and has a pawl at q', which engages with the ratchet-wheel R. This wheel is mounted in the table or carriage C by shaft r, which has a pinion R'. The pinion engages with a rack-bar R², secured to one of the tubes A. It will be seen that on the depression of the pawl p' the ratchet-wheel R can turn one tooth, whereupon the pressure behind piston S' will advance the carriage C a corresponding distance. These devices insure that the carriage, as a whole, shall be retarded during the movements in and out of the cutter-carrier or of that part thereof to which the cutters are secured.

The cylinder S can be detachably clamped with a frame in any suitable way. The rear end is shown as being fastened by a cross-yoke T'.

55 For removing the cuttings positively and drawing them outward use is made of a chain E⁵. This may be actuated in any suitable way. A small rotary air-engine is shown in Figs. 18 to 20. Or the motion of the reciprocating part can, through the medium of proper converting mechanism, be used to drive the main. One form is illustrated in Figs. 8, 9, 10, and others. The piston E' has an arm E³ pivoted thereto at e⁶.

65 e is a pinion mounted on arm E³ by means of shaft e'. This pinion engages with the

parts F F' alternately of a rack, so that as the piston moves out and in there is a continuous rotation in one direction of the pinion. Chain E⁵ should be rotated directly around the shaft e'; but for the purpose of increasing the speed there is shown a larger wheel e² on shaft e' and rotating with wheel e⁵ is another stud-shaft secured to arm E³ and carrying a pinion e³, driven by wheel e², and e⁴ is a sprocket-wheel rotated by pinion e³.

To throw the pinion e from one rack, F, to the other, F', use is made of a guide-bar or plate E², having a way f f', with a rib f², between the upper and lower parts and a cam-latch f³. There is a guide-pin e⁸ on arm E³, which travels in the way and alternately lifts and drops the arm E³ and pinion e. Instead of this mechanism or of the rotary engine, use may be made of any of the mechanisms adapted to accomplish the same purpose.

By means of the devices above described it will be seen that I produce a mechanism in which all of the movements are effected, directly or indirectly, by the pressure of the air.

The operation will be readily understood. If it be supposed that the framework has been properly adjusted in position, and that an aperture has been formed in the material sufficiently large to permit the insertion of the carrier and drills at the end of the wall, (this machine being shown as adapted for "long-wall cutting,") and if it be supposed, further, that the valves j, j', and I' are open, it will be seen that the air, passing through pipe I, will, through duct d², reach the drill-cylinder and cause a rapid reciprocation of the cutter. At the same time the air passes down through pipes L, valve L², and pipe M to cylinder E behind its piston, and will cause it to advance as fast as the material is removed in front of the cutters. As soon as the forward end of the stroke has been reached the valve m² will be tripped by the pin n² and the feed and exhaust in cylinder E reversed, whereupon the cutters and carrier are drawn back. Just as they reach the rear position cam N' lifts rod P, segment P', and lever Q, thereby releasing pawl Q'. The instant this occurs the pressure of the air in cylinder S is allowed to advance the carriage C. Cam N', lever Q, and pawl q' are so related that the instant the lever turns the distance of one tooth the pawl returns and catches the next, thereby stopping the carrier until another cut has been made. At the same time guide-pin n' passes to the lower part o of the way in guide-plate O, and the pin n³ on arm N trips the valve L², so that the piston is again reversed and another advancing movement begins. During these motions of the cutter-carrier to and fro the chain E⁵ is actuated in one or the other of the ways above referred to or in any suitable manner for withdrawing the cuttings. If at any time the path of the cutter-carrier should become clogged, the valves j² and J' can be opened, whereupon air will be

conducted through ports g^3 g^6 with great pressure into the chamber in which the carrier is situated and act to blow out the cutting.

At g' there is shown a supporting antifriction-roller which holds the outer end of the cutter-carrier.

The segment-bar p' is preferably concentric with the plate C, so that in whatever position the wheel D stands the engagement with the lever Q will be at the same point on the latter.

By means of the hand-wheel D^4 , bevel-gear D^3 , and worm-gear D^2 the carrying-table and the cuttings can be thrown into any one of several positions in relation to the main frame—that is, can be so arranged that cutters shall be on a line perpendicular thereto, or they may be inclined in front of or in rear of the perpendicular line.

I have above described some of the ways for embodying the several features of my invention; but I wish it understood that I do not limit myself to the details shown and described in respect to any one of the particular parts shown, as there can be variation in many ways without departing from the essential features of invention. It will also be understood that there are parts mechanically necessary which are not shown in all the details herein, they being devices, such as braces, used for strengthening and additionally supporting the parts which are parallel. A second cylinder similar to that at E can be employed with its piston-rod connected to the cutter-carrier, which will be found advantageous in larger machines, as the carrier and the cutters can be thereby steadied and held firmly to their work.

By examining the drawings it will be seen that the picks or cutters proper h are wide enough to produce a kerf of such depth as to freely admit the cutter-engines II H and the carrier G. I am aware of the fact that use has been heretofore made of a rotary plate or frame placed parallel to the face of the material to be operated on and in a vertical position, and that upon said plate has been arranged a circular series of independent reciprocating cutters or disks adapted to cut a groove in the face of the material, the machines referred to belonging to a class of "channeling-machines." I believe myself to be first to have arranged a series of independent reciprocating cutters and independent cutter-engines on a carrier in a common plane or a straight line in such manner that the engines can be caused to advance, together with their carrier, into the kerf produced by the cutters. It will also be seen that cutters and a cutter-carrier of the kind herein shown and described can be readily applied also in machines of the kind used for "shearing"—that is, effecting a vertical kerf or cut along the "rib" or at the end of the "wall" in "long-wall" mining. With the construction shown it will be understood that the carriage C or the carrier's support D, or both, is provided with slots or openings of

such sort as will permit the proper arrangement of the air-pipes and the parts which project up and down vertically through them. 70

What I claim is—

1. In a mining machine, the combination of the stationary main frame, the carriage, the means for sliding said carriage longitudinally on said frame, a transversely projecting cutter carrier pivoted to the carriage by a vertical pivot, independent cylinders on said carrier, pistons in said cylinders, and cutters attached to the said pistons, all operating, substantially as set forth, to cut the coal transversely of the path of the advance of the carriage. 75

2. In a mining machine, the combination with the stationary main frame, the carriage, a piston and cylinder for sliding said carriage on the main frame, the horizontally swinging cutter carrier pivoted to the said carriage, a piston and cylinder for reciprocating said cutter carrier, independent cutters mounted on said cutter carrier, and independent cylinders 90 and pistons for operating said cutters, substantially as set forth. 85

3. In a mining machine, the combination with the main frame, and the carriage sliding thereon, of the two part cutter carrier, of 95 which one part is movable relatively to the other, a piston and cylinder for moving said part, a series of independent pistons, and cylinders on said movable part of said carrier, cutters attached to said pistons, and means 100 for revolving said cutter carrier on said carriage, substantially as set forth.

4. In a mining machine, the combination with the main frame and the carriage sliding thereon, of the cutter carrier movable relatively to the carriage, independent pistons and cylinders mounted on said carrier, and cutters attached to said pistons, and movable independently of each other, said carrier consisting of two or more flat plates separable 110 in horizontal lines, each having two or more grooves in the interior face, thereby forming feed and exhaust ducts for the said cylinders substantially as set forth. 105

5. In a mining machine, the combination 115 with the stationary bed frame, comprising the tubular side bars, the cross bars, and the supports, of a carriage, the piston and cylinder for sliding said carriage on said tubular side bars, the two part cutter carrier, the cutters 120 secured to one of its parts the pivot connecting the carrier to the carriage, the worm wheel on the carrier concentric with the pivot, the worm on the carriage, and a piston and cylinder for advancing and withdrawing that 125 part of the carrier to which the cutters are attached relatively to the other part, and to the carriage, substantially as set forth.

In testimony whereof I affix my signature in presence of two witnesses.

EDWARD S. MCKINLAY.
